UNITED STATES PATENT OFFICE.

MARSENA R. JULIAN, OF BIRMINGHAM, ALABAMA, MARK H. HOVEY, OF MADISON, WISCONSIN, AND THOMAS E. CLARK, OF DETROIT, MICHIGAN, ASSIGNEES TO JULIAN-BEGGS SIGNAL COMPANY, OF TERRE HAUTE, INDIANA, A CORPORATION OF MAINE.

SPEED-CONTROLLING MECHANISM FOR BLOCK-SIGNAL SYSTEMS.

1,248,663.

Specification of Letters Patent.

Patented Dec. 4, 1917.

Application filed April 22, 1915. Serial No. 23,274.

To all whom it may concern:

Be it known that we, MARSENA R. JULIAN, of Birmingham, Jefferson county, Alabama, MARK H. HOVEY, of Madison, county of Dane, and State of Wisconsin, and THOMAS E. CLARK, of Detroit, county of Wayne, and State of Michigan, all citizens of the United States, have invented certain new and useful Improvements in Speed-Controlling Mechanisms for Block-Signal Systems, of which the following is a specification.

Our present invention relates to new and useful improvements in mechanisms for controlling the speed of vehicles, particularly railway trains, the primary object of our invention being the provision of a speedometer attachment in the form of a circuit breaker which may be driven by the speedometer and included in a circuit controlling the application of the air brakes of the train.

In a copending application filed by us on Apr. 22, 1915, and bearing the Serial No. 23,273, we have fully explained the manner of employing such a device in connection with the cab mechanism of a block signal system, pointing out wherein a speedometer controlled circuit breaker may be utilized to make or break a number of brake controlling circuits at differing speeds to absolutely control the speed of the car under all desired circumstances.

As a rule, we provide means including co-acting contacts for limiting the speed at which the train may travel under the most favorable conditions, means also including another pair of co-acting contacts for limiting the speed at which the train may travel when caution is necessary, and a further means including two additional contacts for controlling and limiting the speed at which the train may be driven in case of danger.

More specifically, the primary object of our present invention consists in the provision of a speedometer driven multiple circuit breaker which may be set to break any of the circuits which it controls, at any desired speed of the vehicle.

A further object of our invention is to so arrange the circuit breaker that it may not only be driven by the driving of the speedometer, but in such a manner that all circuits which it controls are liable to be broken in case the speedometer fails to operate, due

to breaking of its drive belt or equivalent mechanism.

55

A still further object of our invention consists in the provision of a multiple circuit breaker including a plurality of fixed adjustable contacts and a plurality of coacting movable contacts, all adapted for simultaneous movement and all moved through power derived from the speedometer.

60

With these and other objects in view, our invention will be more fully described, illustrated in the accompanying drawings, and then specifically pointed out in the claims which are attached to and form a part of this application.

65

In the drawings:

Figure 1 is a perspective view of the preferred embodiment of our invention;

70

Fig. 2 is a fragmentary side elevational view;

75

Fig. 3 is a front elevation of the contact supporting members and contacts carried thereby;

80

Fig. 4 is a fragmentary sectional view taken on the line 4—4 of Fig. 3 and also illustrating a portion of the speedometer mechanism;

85

Fig. 5 is a transverse sectional view taken on the line 5—5 of Fig. 3;

90

Fig. 6 is a fragmentary elevational view, showing the means for including the drive mechanism of the speedometer in the circuit controlled by the circuit breaker.

95

Corresponding and like parts are referred to in the following description and indicated in all the views of the drawings by the same reference characters.

90

As will be later more clearly apparent, our invention may be readily applied, possibly with some minor structural changes, to practically any type of speedometer now in use and we do not wish, therefore, to limit ourselves to its employment with the particular speedometer illustrated in the drawings, as the speedometer itself forms no part of our invention.

95

In Fig. 1, 10 indicates the casing of a speedometer mechanism which includes a vertically movable cross head 11 traveling upon guide rods 12. This cross head is actuated by the speedometer mechanism, in a manner which need not be explained, in such a way as to move in distances propor-

tion to the speed of the vehicle.

2

tionate to the changes in speed of the vehicle by which the speedometer is driven. The greater the speed of the vehicle the higher this carriage or cross head is raised, of course, being returned to lowered position when the vehicle stops. This cross head, as will be seen by reference to the drawings, forms a part of the regular speedometer structure, carrying as it does the recording needle 13 which co-acts with the movable chart 14. Furthermore, a cord 15, attached to this cross head and passed about suitable pulleys and through a conduit 16, controls the movement of the indicator needle 17 of the speedometer. Directly in front of the guide rods 12 and carriage 11, we place a vertically disposed contact supporting frame, indicated as a whole by the numeral 18, the upper end of this member being, preferably, supported by brackets 19 attached to the upper ends of the guide rods 12. This contact supporting frame should extend in parallel spaced relation to the guide rods and is preferably constructed wholly of fiber, vulcanized rubber or some other insulating material. As best shown in Fig. 3 of the drawings, the supporting member 18 is substantially rectangular in shape, being preferably thickened about its edges to give it additional strength and being formed centrally with a longitudinal slot or opening 20, the ends of which terminate short of the top and bottom of the member 18. This member 18 is further provided with a plurality of parallel spaced apart slots which may vary in number, depending upon the number of circuits which the circuit breaker is to control. In the present instance, three of these slots 21, 22 and 23 are shown. These slots extend throughout nearly the entire length of the body member, as clearly illustrated in Fig. 4 of the drawings, and are provided at the front of the body member with retaining shoulders 24 and at the rear with shoulders 25.

Contacts 26, 27 and 28, in the form of metallic strips, are positioned in these slots 21, 22 and 23, respectively, with their lower ends disposed at the same level and each of these strips is secured in proper position by a clamp screw 29 and thumb nut 30, a washer 31 being preferably interposed between the thumb nut and the rear face of the supporting member 18. It will of course be clear that this arrangement permits ready vertical adjustment of the contact members in their respective slots. Those portions of the slots above the contact plates are preferably closed by filler plates 32 of insulating material, for a reason which will be later explained. These filler plates may be secured against displacement in any suitable manner as by clamping bars 33 and screws 34, this arrangement permitting of their adjustment as the contacts are adjusted. To insure per-

fect alignment of the outer faces of the contact strips with their fillers, their meeting edges may be joined together as shown at 35, if deemed advisable.

A plurality of spring contact fingers 36, 37 and 38 are secured to the lower end portion of the supporting member 18 and engage, at their free ends, against the rear faces of the contact strips 26, 27 and 28, respectively. Wires 39 lead from these contact fingers to binding posts 40, 41 and 42 to which the wires of the circuits to be controlled may be attached. In addition to the fixed contacts above described, the supporting member 18 is further provided with a contact pin 43 located adjacent the lower ends of the contact strips and engaged, at its rear end, by a spring contact finger 44 which is electrically connected to a binding post 45 corresponding to the binding posts 40, 41 and 42.

A rod 46 is secured in any suitable manner to the cross head or carriage 11 and projects at its forward end through the slot 20 of the supporting member 18, the movable contact carrying member 47 being secured upon the outer end of this rod, usually between clamp nuts 48. This contact carrying member 47 is preferably in the form of a metallic bar substantially equal in length to the width of the contact supporting member 18 and its supporting rod 46, preferably, carries a binding screw 49 by means of which a current conducting wire may be electrically connected to the bar 47, the rod 46 being preferably insulated from the cross head 11. The lower portion of the supporting member 18 is provided with a further binding post 50 and a coiled wire 51 connects the binding posts 49 and 50, the coiling of the wire permitting free movement of the contact carrying bar 47.

The contact carrying bar 47 is provided with a plurality of contacts 52, 53, 54 and 55 adapted for electrical engagement with the contact strips 26, 27 and 28 and the contact pin 43, respectively. These contacts carried by the bar may be of any suitable type, those shown consisting of threaded shanks which are adjustable through the bar 47 having milled heads at their outer ends to facilitate this adjustment in order that they may be brought into close sliding engagement with the various contact strips with which they co-act. The ends of these shanks may engage directly against the contact strips or they may be formed with sockets to receive spring pressed contact brushes of silver, as deemed advisable.

At this point, it should be noted that the lower ends of the contact strips and the contact 43 are so arranged that when the cross head or carriage 11 is at its lowest position, the contacts 52, 53 and 54 will engage their respective contact strips and the contact 55

will engage the contact pin 43. In other words, all of the movable contacts will be in engagement with their respective fixed contacts when the speedometer is at rest, that is, when the vehicle is at a halt. It should be further noted that the contact strips are of different lengths in order that their respective movable contacts may pass out of engagement with them at different elevations of the cross head 11, that is, at different indicated speeds of the vehicle.

The longest contact strip 26 is the one employed in governing the brake controlling circuit when the train is running under a clear signal, the strip 27 that employed in governing the brake controlling circuit when the train is running under a caution signal, and the shortest strip 28 that employed when the train is proceeding under a danger signal.

Power is transmitted to the driving mechanism of the speedometer through a metallic belt or chain 56 which is usually trained about a pulley carried by one of the axles of the locomotive or its tender and about a pulley 57 mounted upon the drive shaft 58 of the speedometer. As best indicated in Fig. 5 of the drawings, the hub 59 of the pulley 57 is insulated from the shaft 58 by a fiber bushing 60. This hub is provided with an annular contact ring 61 against which a spring contact 62 bears, this contact being supported in any suitable manner upon the housing of the speedometer as by a bracket 63 insulated from the housing.

As previously set forth, the above described mechanism is primarily intended for use in connection with cab signal systems. When so utilized, leads from the clear, cautionary and danger circuits are connected to the binding posts 40, 41 and 42, respectively, and consequently to the contacts 26, 27 and 28. A lead from a resetting or starting circuit is connected to the binding post 45 and consequently to the contact pin 43. The circuits above named are grounded and a wire is led from the binding post 50 and consequently from the contacts 52, 53, 54 and 55 to an electrically controlled air valve structure or other mechanism to be governed by this device and from such mechanism to the spring contact 62 and so to the ground by the pulley 57 and drive belt or chain 56.

In systems of this nature only one circuit is energized at a time and it will, therefore, be clear that movement of the contact carrying member 47, sufficient to move one of its contacts out of engagement with that contact strip upon the supporting member 18, which is in circuit, will result in a breaking of the circuit. It will further be clear that as movement of the movable contact member 47 is governed by the speedometer mechanism, the breaking of these circuits may be readily regulated and the mechanism set to

break the respective circuits at any desired speeds of the vehicle. By utilizing the spring contact 62, pulley and belt as a part of the circuit controlled, it will be clear that any breaking or disengagement of the belt will result in a breaking of the circuit. We have, therefore, provided a ready means for preventing failure of operation.

It will of course be understood that many changes in details of construction may be made, that the device may be employed with different types of speedometers and that it may be employed not only in connection with block signal systems but upon self-propelled vehicles of any type to control circuits governing vehicle speed. For this reason, we do not wish to limit ourselves to the specific details of construction or to the special use set forth but reserve the right to make any changes both in construction and method of employment permitted by the scope of the appended claims.

Having thus described the invention, what is claimed as new is:

1. An attachment for speedometers including a movable member, contacts carried by and in electrical engagement with said member, a contact supporting member over which the first member moves, and contacts carried by the second member to be engaged by those carried by the first, the contacts carried by the second member being adjustable, whereby they may be disengaged at different times, the contacts of the movable member in one position thereof being in engagement with all of the contacts of the other member.

2. An attachment for speedometers including a movable member adapted for attachment to a speedometer driven element to move therewith, contacts carried by the movable member and in electrical engagement therewith, and a supporting frame over which the movable member passes, said supporting frame carrying a plurality of contact strips for engagement by respective contacts of the movable member, said strips being adjustable in the frame, binding posts carried by the frame, electrical connection between one binding post and the movable member, and a plurality of resilient contact fingers electrically connected with the remaining binding posts and engaging at their free ends against the contact strips.

3. An attachment for speedometers including a member adapted for attachment to a moving speedometer element to move in one direction upon increase in vehicle speed and in the opposite direction upon decrease in vehicle speed, of a supporting element secured to said member, a contact supporting bar carried by the supporting member, a frame of insulating material over which said bar moves, a plurality of contacts carried by and in electrical engagement with the bar, said frame being pro-

- vided with slots, a plurality of contact strips adjustably clamped one in each of the slots for engagement by the contacts of the bar, and a fixed contact carried by the frame, the fixed contact and contact strips in one extreme position of the bar being each engaged by a contact carried by the bar.
4. An attachment for speedometers including a member adapted for attachment to a moving speedometer element to move in one direction upon increase in vehicle speed and in the opposite direction upon decrease in vehicle speed, of a supporting element secured to said member, a contact supporting bar carried by the supporting member, a frame of insulating material over which said bar moves, a plurality of contacts carried by and in electrical engagement with the bar, said frame being provided with slots, a plurality of contact strips adjustably clamped one in each of the slots for engagement by the contacts of the bar, and a fixed contact carried by the frame, the fixed contact and contact strips in one extreme position of the bar being each engaged by a contact carried by the bar, and the contact strips being of differing lengths, whereby they will be disengaged from the contacts of the bar at different positions of the bar.
5. The combination with a speedometer having a driving mechanism and a driven member, the direction and amount of movement of which is dependent upon the speed of the vehicle with which the speedometer coöperates, of a contact supporting frame, a plurality of contact strips of differing lengths supported upon the frame, a contact supporting bar having connection with the movable element to move therewith, a plurality of contacts carried by the bar for engagement with the contact strips, and a contact brush engaging the driving mechanism of the speedometer and forming through such mechanism a ground for the bar.
6. The combination with a speedometer having a movable member, the direction and extent of movement of which is proportionate to the changes in speed of the vehicle, said speedometer also having a driving shaft and a pulley insulated from the shaft, of a commutator ring electrically engaging the pulley, a contact brush engaging the commutator ring, a contact bar carried by the movable member of the speedometer and adapted for electrical connection in a circuit with the brush, a plurality of contacts carried by the bar, and a plurality of contact strips disposed in position to be engaged by the bar during its movement and also adapted for connection in the above circuit.
7. An attachment for speedometers including a plurality of spaced contact strips electrically insulated from each other and adjustable longitudinally of their length, means for independently supplying current to the strips, a member adapted for attachment to a speed governed movable element of a speedometer, and contacts carried by the member one for each contact strip and in electrical connection with the member, each of the contacts in initial position of the member engaging one of the contact strips.
8. In a speed controlling mechanism for vehicles, the combination with a speedometer including a speed governed movable element and a drive mechanism for the element adapted for connection with a moving part of the vehicle, of a member adapted for attachment to the element, means electrically connecting the member with the drive mechanism as long as the drive mechanism remains intact, a plurality of contacts carried by the member and in electrical engagement therewith, and a plurality of contact strips, one for each contact, supported in position to be engaged by their contacts and adapted for connection in branch circuits.
9. In a speed controlling mechanism for vehicles, the combination with a speedometer including a speed governed movable element and a drive mechanism for the element adapted for connection with a moving part of the vehicle, of a member adapted for attachment to the element, means electrically connecting the member with the drive mechanism as long as the drive mechanism remains intact, a plurality of contacts carried by the member and in electrical engagement therewith, a plurality of contact strips, one for each contact, supported in position to be engaged by their contacts and adapted for connection in branch circuits, and means for adjusting the contact strips longitudinally of their length, the member having a movement longitudinally of the length of the strips.
